US0D1074134S

(12) **United States Design Patent** (10) **Patent No.:** **US D1,074,134 S**
(45) **Date of Patent:** **** May 13, 2025**

(54) **CAT-SHAPED PLUSH SLIPPER**

(71) Applicant: **Guangzhou Oupeng Network Technology Co., Ltd.**, Guangdong (CN)

(72) Inventor: **Junjie Chen**, Guangdong (CN)

(**) Term: **15 Years**

(21) Appl. No.: **29/841,331**

(22) Filed: **Jun. 6, 2022**

(51) **LOC (15) Cl.** **02-04**

(52) **U.S. Cl.**

USPC **D2/919**; D2/899

(58) **Field of Classification Search**

(57) **CLAIM**

The ornamental design for a cat-shaped plush slipper, as shown and described.

DESCRIPTION

FIG. 1 is a perspective view of the cat-shaped plush slipper showing my new design;

FIG. 2 is a perspective view thereof from another angle;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-section view taken along line 9-9 in FIG. 7.

1 Claim, 9 Drawing Sheets
